UNITED STATES PATENT OFFICE

2,602,013

FOLDED SHEET DISPENSER

Andrew F. Amerslav, Minneapolis, Minn.

Application February 13, 1950, Serial No. 143,943

4 Claims. (Cl. 312—62)

1

This invention relates to the class of measuring and dispensing devices, and more particularly to a device for dispensing folded sheet articles such as paper napkins, stamp hinges, paper towels, and the like.

An object of this invention is to provide a folded sheet dispenser that will readily dispense folded sheets in a highly sanitary manner.

A further object of the invention is to provide a dispenser for dispensing folded stamp hinges which are gummed on one side singly and sanitarily.

Yet another object of the invention is to provide a folded stamp hinge dispenser that will readily substitute another hinge for one previously dispensed, so that the hinges may be simply, conveniently and individually obtained.

Still further objects of the invention reside in the provision of a stamp hinge dispenser that is strong, durable, highly efficient in operation, simple in construction and design, capable of being readily and easily manufactured, fabricated from a variety of divergent materials, and which is quite inexpensive.

These, together with the various ancillary objects of the invention which will become apparent as the following description proceeds, are attained by this folded sheet dispenser, a preferred embodiment of which has been illustrated in the accompanying drawings, by way of example only, wherein:

Figure 1 is a perspective view of a stamp hinge dispenser embodying the principles of the present invention;

Figure 2 is a vertical sectional view as taken along the line 2—2 in Figure 3;

Figure 3 is a vertical sectional view as taken along the line 3—3 in Figure 2;

Figure 4 is a perspective view of the folded sheet articles such as stamp hinges which are adapted to be dispensed by the novel dispensing device; and

Figure 5 is a perspective view of a combined stop and securing means forming one element of the present invention.

With the continuing reference to the accompanying drawings wherein like reference numerals designate similar parts throughout the various views, reference numeral 10 generally designates an embodiment of the invention used as a dispenser for stamp hinges.

This device comprises a casing 12 having an open end 14. A guide block 16 is slidably mounted in bearing engagement with the top and bottom bearing walls 18 and 20 and the side walls 22 and 24 of the casing.

2

The side walls 22 and 24 are each provided with a notch as indicated at 26 and 28. A looped elastic band 30 is positioned in encompassing relationship around the block 16 and is secured against the side walls 26 and 28 of the casing 12 by means of a combined securing and retaining member generally indicated at 32.

The combined stop and securing member 32 comprises a pair of substantially parallel legs 34 and 36 which are formed at their free ends with pointed hook members 38 and 40, respectively. The legs 34 and 36 are connected by a centrally connected portion 42. The centrally connected portion 42 is positioned to extend across the open end 14 of the casing 12 so as to partially close the opening 14. The hooks 38 and 40 press the elastic member 30 into the grooves 26 and 28, respectively and securely hold the elastic member thereto. A plurality of folded stamp hinges 44 or the like are positioned between the guide block 16 and the central portion 42 and are continuously urged against the central portion 42 by the elastic band 30. Each of the folded sheets 44 are folded twice as best shown in Figure 4 to form zigzag folds. Each of the folds comprise an outer flap 46 and a V-folded sheet 48. The outer flap 46 of successive folded sheets is placed into the V-folded portion of the sheet 44 next adjacent. Then the sheets folded and interfolded are placed into the container 12 with the manifold 46 of the foremost sheet extending through the opening in the open end of the casing 12 above the retaining member 32. The sheets may now be successively withdrawn from the block since the withdrawal of the first sheet will frictionally contact between the members 48 of the successive sheets to cause the flap 46 of the successive sheet to move with the member 48 of the drawn sheet and to project out of the casing 12, an operation which may be repeated until all the sheets have been withdrawn. In order to maintain the frictional contact between the outer flaps and V-shaped portions of the sheets, the elastic member 30 continuously urges the block 16 to press against the sheets 44 so as to continually maintain them in the smallest possible compass to increase friction thereof.

Obviously, the dispensing device as shown may be readily used for other paper or sheet articles than stamp hinges. In addition, the elements forming the invention may be made from a number of divergent materials such as plastics, preferably those made from synthetic thermosetting resins, although metals such as aluminum and stainless steel can be readily used. It is also possible to make the block 16 of wood and make

the casing 12 of pasteboard or similar material.

Since from the foregoing the construction and advantages of this dispensing device are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be resorted to which fall within the scope of the appended claims.

Having described the invention, what is claimed as new is:

1. A dispensing device for folded sheets comprising a casing having an open end, a guide block slidable in said casing, an elastic band engaging said guide block urging said guide block toward said open end, said casing having opposed recesses adjacent said open end and combined stop and securing means partially closing said open end and securing said band in said recesses in said casing.

2. A dispensing device for folded sheets comprising a casing having an open end, a guide block slidable in said casing, an elastic band engaging said guide block urging said guide block toward said open end, said casing having opposed recesses adjacent said open end and combined stop and securing means partially closing said open end and securing said band against said casing, said combined stop and securing means comprising a resilient substantially U-shaped member having a pair of substantially parallel legs attached to a central connecting portion, said legs having hooks engaging the ends of said band and holding said ends in said recesses, said central portion extending across said open end.

3. A dispensing device for folded sheets com-

prising a casing having an open end, a guide block slidable in said casing, an elastic band engaging said guide block urging said guide block toward said open end, said casing having opposed recesses adjacent said open end and combined stop and securing means partially closing said open end and securing said band against said casing, said combined stop and securing means comprising a resilient substantially U-shaped member having a pair of substantially parallel legs attached to a central connecting portion, said legs having hooks engaging the ends of said band and holding said ends in said recesses.

4. A dispensing side for folded sheets comprising a casing having an open end, a guide block slidable in said casing, resilient means engaging said guide block urging said guide block toward said open end, and combined stop and securing means partially closing said open end and securing said resilient means against said casing, said combined stop and securing means comprising a substantially U-shaped member having a pair of substantially parallel legs attached to a central connecting portion, said legs engaging said casing, said central portion extending across said open end, and hook means on said legs engaging matching recesses in said casing, said resilient means comprising an elastic member positioned between the legs of said U-shaped member and the casing and engaged by said hook means with- in said recesses.
